EXTENSION TABLE WITH ADDITIVE LEAF

Herbert F. Lyon, Memphis, Tenn.

Application November 13, 1948, Serial No. 59,834

1 Claim. (Cl. 311—48)

1 This invention relates to an extension table, and particularly to an extension table having a top member preferably in one undivided piece and hinged drop leaves at its ends by which its length may be increased, in which table provision is also made for the insertion of a leaf or leaves between the solid top and the drop leaves.

The objects of the invention are:

To provide as an article of furniture a table having an uninterrupted top together with an additive leaf adapted for positioning at the end of the table top and means for supporting the additive leaf in such position to accomplish extension of said table;

To provide an extension table of simple and efficient construction adapted for practical and economic manufacture;

To provide smooth and unbroken side rails when the table is unextended;

To provide an extension table and filler leaf in which the leaf is housed within the table when not in use;

To provide means for efficiently supporting and lining up the filler leaf for use;

To provide hinge means for lining up the drop leaves; and

To provide simple and efficient means for accomplishing the extension of the table and limiting such extension.

The means by which the foregoing and other objects are accomplished and the manner of their accomplishment will readily be understood from the following specification on reference to the accompanying drawings, in which:

Fig. 1 is a side elevation of the table overextended and with the filler leaf loosely placed.

Fig. 2 is a corresponding plan view.

Fig. 3 is a sectional plan taken on the line III—III of Fig. 1 showing fragmentary portions of the side rail and complementary slide rail and the slide and stop members respectively carried by each.

Fig. 4 is a sectional elevation taken on the line IV—IV of Fig. 2.

Fig. 5 is a sectional elevation taken on the line V—V of Fig. 2.

Fig. 6 is a fragmentary sectional elevation taken on the line VI—VI of Fig. 5.

Fig. 7 is a sectional elevation of one end of the table taken on the line VII—VII of Fig. 8.

Fig. 8 is a sectional cross elevation of the table taken on the line VIII—VIII of Fig. 7; and

Fig. 9 is a section on the line IX—IX of Fig. 1 showing the hinge attachment of the drop leaf.

Referring now to the drawings in which the

2 various parts are indicated by numerals, 12 is a solid table top which overlies and is rigidly secured at its opposite sides to side rails 14, and at one end to an end rail 16, and is supported by a leg 18 solidly secured to the end rail 16 at its center. Slide rails 20 are secured at their outer ends to an oppositely disposed end rail 22, the latter end rail also being solidly secured to and supported by a single leg 24. Inwardly of the leg the side rails are additionally secured to opposite ends of a cross rail 26 which also is preferably secured to the inner side of the leg 24. Adjacent their inner ends the slide rails are further secured to and braced apart by an auxiliary cross rail 27.

20 The slide rails 20 are disposed between the side rails 14 and in respective sliding contact therewith, the contacting faces of the rails being respectively provided with complementary grooves 14A and 20A. A block 28 of cross section to fill the grooves 14A and 20A of the complementary side and slide rails is rigidly secured in the groove 14A of the side rail adjacent its free end, and a similar block 30 is secured in the 25 groove 20A of the slide rail at its free end, the block 28 being slidable in the groove 20A and the block 30 being slidable in the groove 14A, the two blocks cooperating to limit extension movement of the sliding rails with respect to the side rails. The ends of the side rails 14 are provided with halved end portions 14B which overlap and hide the ends of the end rail 16, and when the table is not extended also overlap and hide the end rails 22, presenting a finished and pleasing side appearance.

30 Hinged to the opposite end rails 16 and 22, as by hinges 34, are drop leaves 36 of the table top, which leaves hang downward from the hinges but which may be turned into horizontal position to extend the length of the table either at one or both ends. When raised the extending portion of the drop ends are supported by braces 38 of well known type.

35 The end edges 12A of the top extend slightly beyond the end rails 16 and 22 and may be accurately undercut, the complementary edges 36A of the drop leaves being correspondingly overcut to form mating edges, or the edges of the table top may be overcut in the manner shown for the drop leaves and the leaves correspondingly undercut.

40 The hinges are pin connected flat strap hinges, one half of each hinge (Fig. 9) being solidly secured to the top of the end rail 22 of the sliding section with its upper surface flush with the

top of the rail and its hinge pin offset laterally outward beyond the outer face of the rail, and its other half secured to the under surface of the drop leaf, in order that when the drop leaf is raised to horizontal the edge 36A of the drop leaf will be supported by the hinge half and held in underlying contact with the under cut edge 12A of the table top 12 and the top surface of the leaf lined flush with the surface of the table top.

Extending between the cross rail 27 and the end rail 22 is a rod 40, and between the cross rails 26 and 27 is a second or support rod 42 which is laterally offset from, and below the rod 40. Supported from the rod 40 by oscillatable brackets 44 is a filler leaf 46 transversely cut into halves 46A, 46B which are connected by hinges 48 to fold flat together for storage and open out to full length for use, the length of the leaf when opened out for use being identical with the width of the table and its edges under and over cut complementary to the drop leaf and table top edges 36A and 12A (Fig. 9). When folded the filler leaf 46 is turned about the rod 40 into the space between the slide rails 20 and the leaf half 46B supported by the rod 42, the entire leaf being below the level of the table top 12.

The table when unextended presents a smooth unbroken top 12 and side rails 14, and the drop leaves 36 may be allowed to hang down and complete a compact and finished table.

Where a longer table is desired one or both the drop leaves 36 may be raised and supported in raised position.

To further lengthen the table the sliding end is pulled out uncovering the filler leaf 46, such action being limited by the blocks 28 and 30 (Fig. 3). The folded filler leaf 46 is raised from the support rod 42 (Fig. 8) and pivotally swung about the rod 40 until the half 46A rests on one of the rails 20, and the other half 46B unfolded to rest on the other of the rails 20. The two sections are then moved together clamping the filler leaf between the end edge of the top 12, and the inner edge of the drop leaf. This closing movement brings the end rail 22 into supporting position beneath the outer edge of the filler leaf and the auxiliary rail 25 into supporting position intermediate the width of the leaf and effects a stable support for the leaf. The undercut end 12A of the table top prevents any unforeseen upward bulging of the leaf at the center and substantially insures smooth surface alignment of the top and leaf.

The housing of the leaf insures that it will be available at all times for use and substantially insures that no warping and consequent ill fitting such as often occurs when leaves stand around for indefinite periods, will occur.

It will be understood that two pedestal legs are shown for purposes of illustration, but that four legs of usual type may be used if so desired.

It will be understood that two pedestal legs 46 is placed at an end of the table top rather than in the usual manner between sections of such top, and is therefore an additive leaf rather than a filler or insertable leaf.

I claim:

1 claim.
An extension table comprising complementary sections, an additive leaf and hingedly attached drop leaves at the opposite end of said table, each section including an end rail and supporting leg means; a first of said sections including uninterrupted side rails of length to extend from end rail to end rail, and an uninterrupted top secured to said rails, said top being of width and length to overlie said side rails and said end rails and having undercut end edges, and when said table is not extended, completing with said rails a finished table with uninterrupted top, side and end rails; the second of said sections including 0 side rails extending from its said end rail between and in cooperative telescopic engagement against the inner sides of the side rails of said first section, and being retractable from said first section to receive said leaf, said leaf being 5 portable by the rails of said second section in contact with the proximate end of said top when said second section is retracted, to extend the length of said table, said drop leaves being hinged each to a proximate end rail, and being each 10 provided with bracing means cooperating with the related said proximate rail for support of the related said drop leaf in raised position; said drop leaves having their rail proximate edges overcut complementary to the end edges of said 15 top, said insertable leaf having an overcut side edge complementary to the proximate undercut end of said top, restraining upward displacement of said leaf, the opposite edge of said leaf being undercut for engagement by the proximate edge 20 of the related said raised drop leaf and being restrained against movement endwise of said table by said drop leaf.
